UNITED STATES PATENT OFFICE.

ANTHONY NAINKA, OF JANEVILLE, WISCONSIN.

SHAMPOOING APPARATUS.

1,329,058.

Specification of Letters Patent. Patented Jan. 27, 1920.

Application filed September 2, 1919. Serial No. 321,091.

To all whom it may concern:

Be it known that I, ANTHONY NAINKA, a citizen of the United States, residing at Janesville, in the county of Rock and State 5 of Wisconsin, have invented a new and useful Shampooing Apparatus, of which the following is a specification.

The present invention relates to shampooing chairs; its principal object being to provide a chair wherein a person may conveniently recline while being shampooed.

Still another object of the invention resides in a provision of a chair which will enable a person to recline while being shampooed or having the head otherwise treated, and which will prevent the person from becoming wet other than the parts being treated.

It is a further object of the invention to provide a chair of this type which embodies a bowl or receptacle which underlies the person's head so as to catch the water while the person's head is being shampooed or washed.

Another object of the invention is to provide a reclining shampooing chair having a basin or bowl associated therewith together with a head rest that may be swung to a position to one side of the bowl when not in use and which may be locked in position over the bowl or basin.

Another object of the invention resides in the provision of a chair of this character which is provided with reservoirs for containing the water, adapted to be conducted to a basin or bowl at the upper end of the chair, the construction being such as to facilitate the shampooing operation and to overcome the disadvantage of the person going to a wash basin to perform the rinsing operation.

Another general object of the invention is to provide a shampooing apparatus having the above characteristics which is simple in construction, which consists of few parts, and which may be manufactured and sold at minimum cost.

With the above and other objects and advantages in mind, the invention consists of 50 the combinations of elements, constructions and arrangements of parts, operations and general assemblage, all of which will be hereinafter enlarged upon and set forth in

the appended claims, the invention being illustrated in the attached drawings, where- 55 in:

Figure 1, is a side elevation of a shampooing chair constructed in accordance with my invention;

Fig. 2, is a plan view of the same; 60

Figs. 3 and 4, are detail views of the head rest lock.

Referring to the drawing wherein like characters of reference designate like parts in all the views the numeral 5 designates a 65 standard or base upon which the chair 10 is mounted. The chair is of the reclining type and is capable of angular adjustment.

A plurality of parallel guide bars 11 extend from the chair 10 and mounted for 70 vertical movement thereon are tanks or reservoirs 12. Flexible elements 13 are attached to the tanks and are engaged with pulleys 14 at the upper ends of the guides and are fastened as at 15. These tanks when 75 filled are raised to the upper ends of the guides so that they will be out of the way. When it is desired to replenish the supply of water these tanks are lowered by means of the flexible elements 13. Rubber conduits 80 16 lead from the tanks 12 and communicate with a discharge tube 17. While (not shown) any type of spray or head may be associated with the tube 17.

A basin or bowl 18 is employed which is 85 supported on a Y-shaped bracket 19 mounted for vertical adjustment in guides 20 on the back of the chair 10. One leg of the Y-shaped member underlies the basin and terminates in a hook 19' for supporting the 90 discharge tube 17 when not in use.

The forward wall of the basin or bowl is cut away as at 21 to accommodate the person's neck and is padded with any desirable material. Guide flanges 21' are arranged 95 at opposite sides of the bowl at the forward end thereof in which a shield or protector 22 is removably mounted, the protector 22 being slidable between the guide flanges 21' to permit the same to be secured to the bowl. 100 The inner edge of the protector 22 is cut out as at 23 to loosely receive the person's neck.

From the foregoing it is obvious that the protector 22, may be positioned in the flanges 21', when a person has been properly 105 positioned in the chair, the cut out portion

of the protector 22 encircling the forward portion of the neck of the person, the body portion thereof extending over the collar or front portion of the apparel of the person, thus protecting the person from the water and soap, which usually drips onto the person's clothing.

An outstanding ear 23' is disposed at one side of the forward wall of the basin and is 10 provided with an inclined trackway 24 and a lug receiving opening 25 at the highest point of the trackway. A head rest is designated at 26 and is supported on a pair of divergent rods 26', one of which is supported for pivotal movement in the ear 23. The shield 22 is positioned between the flanges 21', whereby the shield 22 is removably supported on the bowl 18. An outstanding lug 27 is carried by one of the rods 20 and is movable over the trackway 24 and adapted to engage in the opening 25 therein to retain the head rest against movement over the basin. The opposite end of the ear 23 extends laterally and constitutes a stop 25 28 adapted to be engaged by the lug 27 on the head rest when the latter is swung to one side of the basin.

From the disclosure it will be apparent that the head rest overlies the bowl 18 and 30 that the person's head rests thereon with the neck disposed in the cut out parts of the basin and shield. It will also be obvious that owing to the height of the tank the water will flow therefrom with sufficient 35 pressure.

This embodiment of the invention is illustrative only and it will be understood that the same may be modified in many respects and that such limits of modification are only 40 governed by what is claimed.

What is claimed is:

1. In a shampooing apparatus, a chair, a bowl mounted thereon and having its edge cut out to receive the person's neck, a head rest hingedly connected to the bowl and 45 capable of being disposed over the bowl or to one side thereof, and a removable protector plate to be disposed in the forward end of the bowl.

2. In a shampooing apparatus, a chair, a 50 basin supported thereon, an outstanding ear carried by the basin having one face thereof inclined and provided with a lug receiving recess at the highest point of the inclined face, a head rest including a supporting rod 55 having one end rotatably mounted in the ear, and a lug carried by the rod and movable over the inclined face of the ear and adapted to be engaged in the recess to lock the supporting rod against movement, and 60 a stop extending from the ear to engage the lug upon swinging the head rest in the reverse direction.

3. In a shampooing apparatus, a chair, a bowl supported adjacent the chair, said 65 bowl having a cut out portion in the forward portion thereof, a removable protector having a cut out portion co-operating with the cut out portion of the bowl, for providing a neck receiving opening, a head rest 70 supported by the bowl, and means for supporting the head rest to permit the same to be moved into and out of operation.

In testimony that I claim the foregoing as my own I have hereto affixed my signature in the presence of two witnesses.

ANTHONY NAINKA.

Witnesses:

M. FRANC EDWARDS,
HOWARD W. LEE.
